Patented May 30, 1922.

UNITED STATES PATENT OFFICE.

GEORGE S. WILCOX, OF BURKBURNETT, TEXAS.

PUMP VALVE.

1,418,043.

Specification of Letters Patent. Patented May 30, 1922.

Application filed June 17, 1920. Serial No. 389,724.

To all whom it may concern:

Be it known that I, GEORGE S. WILCOX, a citizen of the United States, residing at Burkburnett, in the county of Wichita and State of Texas, have invented certain new and useful Improvements in Pump Valves; and I do declare the following to be a full, clear, and exact description of the invention, such as will enable others skilled in the art to which it appertains to make and use the same.

This invention relates to an improved valve and one object of the invention is to provide the valve with a construction in which the movable valve member may be driven back upon its seat in case the valve member becomes stuck in the valve cage.

Another object of the invention is to so construct the valve that the improved cage and valve striking follower may be connected with a conventional construction of pump head, the follower being yieldably held in a raised position and adapted to move longitudinally for striking the valve ball, or other type of valve member.

Another object of the invention is to so construct this valve that the follower carried by the standing valve may be struck by the reciprocating pumping valve and thus the follower moved downwardly to engage the valve ball and drive the same back into place upon its seat.

Another object of the invention is to so construct the valve that the follower of the reciprocating valve may be held against longitudinal movement except when the reciprocating valve strikes the follower of the standing valve a relatively severe blow.

Another object of the invention is to so construct this device that sand, fragments of rock, pieces of cup which are formed of leather and other material which may cause the valve to be held in a raised position and prevent it from seating properly may be cut loose.

This invention is illustrated in the accompanying drawings, wherein:

Figure 1 is a view showing the pump barrel or tube in vertical section and a standing valve and reciprocating valve positioned therein shown in elevation.

Figure 2 is a view similar to Fig. 1 show-

ing the standing valve and reciprocating valve partially in elevation and partially in longitudinal or vertical section,

Figure 3 is a transverse sectional view taken along the line 3—3 of Fig. 2, and

Figure 4 is an enlarged view showing the elements of the improved device in vertical section.

This valve seating device may be used in connection with a standing valve 1 or with a reciprocating piston 2, the standing valve and pump head being provided with a conventional construction and each including the usual valve seat 3 upon which the ball valve 4 rests when in a closed position. The pump head also includes the usual striker 5. The standing valve is positioned in the lower portion of the pump barrel 6 and the reciprocating pump head will be connected with the pump rod 7 through the medium of a coupling block 8 as will be hereinafter more specifically brought out.

In pumps such as are now in use, it is customary to provide a valve housing for the standing valve so that the valve ball will be restrained in its movement and guided during its movement under action of the oil or other liquid which is drawn through the standing valve by the reciprocating piston. When thick oil is being pumped, this oil will cake in the valve cage and cause the ball valve to stick in the cage out of engagement with its seat 3 and it also often happens that sand and small portions of rock or pieces of leather from the washers of the standing valve will adhere to the valve ball or will clog the valve cage beneath the valve ball and thus prevent this valve ball from seating upon its seat 3.

It is then necessary to lower the pump rod so that the reciprocating pump head extends down into the tube or barrel 6 a sufficient distance to strike the standing valve. When the pump rod is lowered, the proper amount and the striker 5 strikes the upper end of the valve cage, it causes the valve ball to vibrate a certain amount and this will, in some cases, cause the valve ball to drop back upon its seat or if the cage is clogged, the vibration will in some cases be sufficient to cause the obstruction to work loose. At other times

this is not effective in clearing the standing

valve or piston in case it is the piston which has become clogged, and it is then necessary to withdraw the pump rod and piston from the barrel and then lower a fishing tool and withdraw the standing valve. This requires a great deal of time and is very expensive and therefore in order to permit the cage of the standing valve or piston to be cleared while still in the barrel 6, this improved construction has been provided.

In this construction, the usual cage is removed and a cage 9 put in place. This cage 9 is somewhat longer than the usual cage and has its opening 10 unthreaded instead of being threaded for receiving the threaded portion of a fishing tool. A follower 11 extends through the threaded opening 10 in the head of this cage 9 and has its lower end provided with a cup 12 which limits upward movement of the follower through the opening. This cup is of sufficient size to have free sliding movement in the cage and is formed as a cup instead of a solid head so that a cutting edge 13 is provided which will engage the valve ball and serve to cut sand and other material from the ball. The upper end portion of the follower is threaded as shown at 14 and the threaded upper end of the follower for the reciprocating pump head is screwed into a threaded opening 16 formed in the block 8 thus releasably connecting the piston with the block. The upper end of the follower for the standing valve is screwed into a threaded opening formed in the lower portion of a crown 15 which crown is provided with a threaded opening 17 to receive the threaded end portion of a fishing tool. A spring 18 which is a relatively light spring is positioned upon the follower of the standing valve between the crown 15 and the upper end of the cage 9 and a similar spring 19 which is a relatively heavy spring is positioned about the follower of the reciprocating piston between the block 8 and the upper end of the valve cage. It will thus be seen that although both followers are permitted of longitudinal sliding movement, a greater force will be required to move the follower of the piston than will be required for moving the follower of the standing valve.

When this device is in use, the standing valve is positioned in the lower portion of the pump barrel and the reciprocating piston will be connected with the lower section of the pump rod by screwing the threaded end portion of the block 8 into the socket of the pump rod section. The pump will be operated in the usual manner with the piston reciprocating in the pump barrel and the oil or other liquid first passing through the standing valve 1 and then through the reciprocating piston which serves to lift the oil in the pump barrel and force the same out through the upper end of this pump barrel.

If the standing valve becomes choked, by heavy oil or becomes clogged by sand or any other material, the valve ball will not seat properly upon its seat and the pump rod can then be lowered into the well a sufficient distance to permit the striker to engage the crown 15. The pump will then be operated in the usual manner and as it reciprocates, the striker will strike the crown and drive the follower 11 of the standing valve downwardly against the action of the spring 18. The cup or head of this follower will strike the valve ball and thus drive the ball downwardly towards its seating position. The passage of the fluid through the standing valve will tend to rotate the valve ball and thus sand and other substances which may be adhered to the valve ball will be cut away by the cutting edge 13. Pieces of leather and other material in the lower portion of the cage or wedged between the valve ball and the arms of the cage will not serve to prevent reseating of the valve, as this device does not depend simply upon vibration but depends upon a positive blow delivered to the valve ball. By having the spring 19 relatively heavy the striker 5 may strike the crown and impart movement to the plunger of the standing valve without the plunger of the piston being moved longitudinally through the valve cage thereof and further when the pump is in operation, the follower of the piston will be prevented from having longitudinal sliding movement which might interfere with proper pumping operations. When it is necessary to remove an obstruction in the valve cage of the piston, it is simply necessary to permit the pump rod to extend down into the pump barrel a greater extent than in the previous case. Therefore, the follower of the standing valve will be moved downwardly to its full extent and a continued downward movement of the pump rod will cause the follower of the piston to move downwardly against the action of the spring 19. The head of this follower will, therefore, engage the valve ball of the piston and obstruction in the cage of the piston and the valve ball therein caused to seat properly. It has been stated that this will be used in connection with a standing valve and piston having a valve ball but it is to be understood that this device can be used in connection with any type of movable valve where the valve is positioned in the valve cage for vertical movement therein. It will thus be seen that with this device the valve cage of the standing valve or piston can be very easily cleaned and the valve caused to seat properly without it being necessary to remove the pump rod, piston and standing valve from the pump barrel.

While this invention is particularly adapted for use in connection with deep

well pumps such as are used in oil wells, it will be understood that the invention may be used in connection with various kinds of pumps. It will be further understood that various changes in the form, proportion and arrangement of parts may be resorted to within the spirit and scope of the invention.

I claim:

1. A structure of the character described including a standing valve having a movably mounted valve member, a piston slidably mounted above the standing valve and including a movable valve member, means for positively engaging and moving the valve member of the standing valve into a closed position yieldably held out of engagement with the valve member and positioned for engagement by the piston, and means for moving the valve member of the piston to a closed position yieldably held out of engagement with the valve member.

2. In a structure of the character described, a standing valve having a movably mounted valve element, a slidably mounted follower yieldably held out of position for engagement with the valve member, a reciprocating piston slidably mounted above the standing pump valve for engaging the follower and moving the same to positively engage the valve member, the piston including a valve cage, a valve member movably mounted therein, a follower slidably mounted for movement into and out of position for engaging the valve member of the piston, a block carried by the follower of the piston for connection with a pump rod, and resilient means positioned about the follower of the piston and engaging the block

to yieldably retain the follower in a raised position.

3. A structure of the character described comprising a standing valve including a movable valve member, means for returning the valve member to a closed position when held out of a closed position, a piston for imparting movement to the last mentioned means and including a movably mounted valve member, and means for returning the valve of the piston to a closed position when held out of a closed position, the last mentioned means being adapted for connection with a pump rod and being yieldably held in an inoperative position.

4. A piston having a movably mounted valve element, slidably mounted means for returning the valve element to a closed position when held out of a closed position, means for connecting the last mentioned means with a pump rod, and means for yieldably retaining the valve returning means in an inoperative position.

5. In a pump, the combination of a pump barrel, a reciprocating piston arranged in the barrel, a check valve in said piston movable toward and from its seat, and valve reseating means carried by the piston and normally inactive during the operation of the pump, said valve reseating means being operable from the exterior of the pump barrel by movement of the piston beyond its normal stroke for engaging the valve and forcing it positively toward its seat.

In testimony whereof I have hereunto set my hand.

GEORGE S. WILCOX.
